UNITED STATES PATENT OFFICE.

HAZEL E. PALMER, OF KANSAS CITY, KANSAS.

NATURAL-SHELL PERFUME LAMP.

Application filed April 11, 1924. Serial No. 705,963.

To all whom it may concern:

Be it known that I, HAZEL E. PALMER, a citizen of the United States, residing at Kansas City, in the county of Wyandotte 5 and State of Kansas, have invented certain new and useful Improvements in Natural-Shell Perfume Lamps, of which the following is a complete specification.

In general, the present invention relates 10 to a new article of manufacture, which I have called, natural shell perfume lamp, and includes among its many novel features a natural shell receptacle for liquid perfume or toilet water.

15 The primary object of this invention is to provide a new and ornamental perfume lamp, composed entirely of natural shells and grouped about an incandescent electric light lamp in such a way as to resemble a 20 large blossom.

Another object of the invention is the provision of a novel article of ornamentation, composed in the main of natural shells and having the appearance of a flower, 25 which has a base and supporting means formed by the coiled stem of said flower.

A still further object of the present invention is to provide a combination ornamental lamp and perfume burner, constructed 30 of natural shells of different shapes and tinted to lend harmony and blend with the color of a particular light bulb which may be used to illuminate the creation and heat the perfume to a point of vaporization.

35 With these general objects in view, as well as other objects which will appear in the course of the detailed specification, the invention will now be described with reference to the accompanying drawings illustrating 40 but one construction embodying the improvements, after which the novel features of the same will be set forth and defined in the appended claims.

In the drawings:

45 Figure 1 is a front elevation of a perfume lamp constructed in accordance with this invention.

Fig. 2 is a top view of the same.

Fig. 3 is a back view of the natural shell 50 perfume lamp.

Fig. 4 is a vertical central section of a portion of the flower center, having parts broken away to clearly illustrate construction.

55 Fig. 5 is an enlarged detail view of the "flat" shell unit; and

Fig. 6 is a fragmentary detail view of the center shell unit showing the method of stringing.

Referring now to the drawings in detail, 60 wherein similar reference characters refer to like parts throughout the several views, these illustrate the construction of a natural shell perfume lamp in one of its forms only, and it must be understood that natural sea 65 or fresh water shells of any kind or description may be used to form the blossom proper which is supported by suitably coiling the metal rod 7 to form a base 8 and stem 9.

A small electric light socket 10 is attached 70 by any suitable means or method to the upper end of rod 7 for the reception of a lamp 11, colored to suit the desire of the user and to harmonize with the coloring of the many shells grouped about it. Flower centers 12, 75 bound tightly about the periphery of socket 10 by wire or other means 13, lie close to the base of lamp 11 to conceal socket 10 from view. Rubber and friction tape is further used to bind the parts to rod 7 and 80 socket 10.

One of the most important features of this invention is the natural shell container 85 14, located adjacent lamp 11 where liquid perfume (not here shown) receives heat and is vaporized. In this particular design, the shells used are known as bleeding teeth shells and are supported in contact with lamp 11, as shown in Fig. 4, by an ar- 90 cuate pliable wire or other suitable means 15, which is used to adjust the container toward and away from the source of heat, and thereby control the rapidity of evapo- 95 ration, and is bound to rod 7 and socket 10 by tape or wire as previously set forth. Two 100 of such containers are here illustrated, but any number may be used to suit the size and design of the shellwork, and by the pliable wire means of holding them, the containers and amount of evaporation may be adjust- 105 ed and controlled by removing or supplying containers as desired.

Arranged circumferentially around socket 10, are a plurality of shell units 16 comprising a number of spiral, cone-shaped periwinkle or small conch univalve shells 17, strung on wire 18 and bound to rod 7 to form an artistic flower center as shown in Fig. 1.

110 It has been found in practice, that these shells 17 may also be used to hold perfume either in a liquid state or on small tufts of

cotton. The lamp 11 will heat the same and cause evaporation when burning, and the same pleasing result is attained as by employing a special container. These units 5 may be adjusted to cause the creation to assume different appearances resembling the different flowers, and to correspond to the particular kind of perfume being vaporized.

For leaves and the back of this shell flower, 10 a number of bivalve cockle or similar semi-flat shells 19 may be used, which are also grouped in units and have from three to five shells strung on wire 20 as illustrated in Fig. 4. These units are arranged around 15 rod 7 and bound thereto by wire 21.

All the exposed wires 20, wires 15, and rod 7 are wrapped with green chenille 22, thus giving a more natural appearance to the creation.

20 This natural effect is augmented by the tinting of all the shells. For instance, the bivalve shells 19 are tinted green with suitable touches of blue or other color to give an artistic touch, while the center per 25 winkle shells 17 are given other shades such as yellow, pink, purple or gold to resemble natural flower colors. All tinting and painting is done with glossy colors to give "sparkle" to the lamp.

30 As will be noticed from the drawings, the shells are drilled to provide means for stringing them on the wires, and the units are preferably wrapped with ribbon or chenille 22 before they are bound around the 35 socket 10 and supporting rod 7. It has been found advisable to coat the wire or rod to be covered with glue before wrapping with the binding material.

Cotton covered wire should be used in the 40 case of the wire 18, which permits its being painted the same color as shells 17.

While I have illustrated and described what now is deemed to constitute one of the preferred forms of embodiment of the invention, I desire to reserve the right to make 45 all such formal changes or modifications as may fairly fall within the scope of the appended claims.

Having described the invention, what I 50 claim is:

1. In a perfume lamp having means for heating and lighting said lamp, a plurality of natural shell containers for the liquid to be vaporized, each of said natural shell containers being supported in contact with said heating and lighting means by an arcuate pliable connection, whereby the container may be adjusted toward and away from the heating means.

2. In a perfume lamp of the kind described, the combination with a blossom shaped body, of a center therefor having a lamp disposed at an angle, a coiled support therefor, a natural shell perfume container positioned horizontally and having its under side in direct contact with said lamp and maintained in said position by pliable connections to said coiled support. 60 65

3. In a perfume lamp of the kind described, the combination with a blossom shaped body composed of natural shells, of a center therefor having a lamp disposed at an angle and rigidly attached to the coiled support of said body and a perfume container carried in a horizontal plane with a portion only of its arcuate bottom in contact with said lamp. 70 75

4. In a perfume lamp of the kind described, the combination with a blossom shaped body composed of natural shells and having a coiled support, of a center therefor having a lamp disposed at an angle and rigidly attached to the upper end of said coiled support, a natural shell perfume container having perforations therein, means engaging said perforations and attached to said coiled support whereby the perfume container may be adjusted to the desired proximity to said lamp. 80 85

5. In a perfume lamp of the kind described, the combination with a blossom shaped body composed of natural shells and having a coiled support resembling a blossom stem, of a center therefor having a lamp disposed at an angle and rigidly attached at the upper end of said coiled support, a perfume container having perforations in its side adjacent the rim, a pliable wire support passing through said perforations and twisted back upon itself to form an adjustable means for attaching said container to the coiled support, whereby said perfume container may be adjusted to the desired proximity to said lamp. 90 95 100

6. In a perfume lamp having a heating and lighting lamp and a coiled support, a plurality of perforated perfume containers grouped around said lamp and supported by pliable wire passing through said perforations, said wire being rigidly attached at its one end to said coiled support and adapted to be formed about said heating and lighting lamp to form an imitation blossom corresponding to the kind of perfume being vaporized by the heat from said lamp. 105 110 115

In testimony whereof I hereunto set my hand this 4th day of April, 1924.

HAZEL E. PALMER.
